UNITED STATES PATENT OFFICE

113,547

DESIGN FOR A DINNER WAGON

Louis William Boulton, Port Arthur, Ontario,
Canada

Application August 15, 1938, Serial No. 79,361
In Canada June 16, 1938

Term of patent 7 years

To all whom it may concern:

Be it known that I, Louis William Boulton, a subject of the King of Great Britain and resident of the city of Port Arthur, district of Thunder Bay, Province of Ontario, in the Dominion of Canada, have invented a new, original, and ornamental Design for a Dinner Wagon, of which the following is a specification, reference being had

to the accompanying drawing, forming part thereof.

The drawing represents a perspective view of the dinner wagon showing my new design.

I claim:

The ornamental design for a dinner wagon, as shown.

LOUIS WILLIAM BOULTON.
